UNITED STATES PATENT OFFICE

149,622

DESIGN FOR A FRUIT SLICING UTENSIL

James D. Dougherty, Minneapolis, Minn.

Application July 25, 1946, Serial No. 131,925

Term of patent 14 years

(Cl. D22-3)

To all whom it may concern:

Be it known that I, James D. Dougherty, a citizen of the United States, residing at Minneapolis, in the county of Hennepin and State of Minnesota, have invented a new, original, and ornamental Design for Fruit Slicing Utensils, of which the following is a specification, reference being had to the accompanying drawings, forming part thereof.

Referring to the drawings:

Fig. 1 is a top plan view of a fruit slicing utensil, showing my novel design; and

Fig. 2 is a sectional view taken on the line 2-2 of Fig. 1.

The essential features of my design reside in the portions shown in full lines.

I claim:

The ornamental design for a fruit slicing utensil, as shown and described.

JAMES D. DOUGHERTY.
